(57) **CLAIM**

The ornamental design for a chainguard for bicycles as shown and described.

DESCRIPTION

1. Chainguard for bicycles

1.1 is a front perspective view of a chainguard for bicycles embodying our new design;

1.2 is a front elevation view thereof;

1.3 is a rear elevation view thereof;

1.4 is a rear perspective view thereof;

1.5 is a bottom plan view thereof;

1.6 is a right side elevation view thereof; and

1.7 is a top plan view thereof.

Design no. 1 relates to a chainguard for a bicycle; the parts shown by means of dotted lines are not part of the claimed design; the thin lines in the representations represent con-

(Continued)

tours, and do not illustrate an ornamentation or decoration on the surface of the chainguard; no colour is claimed.
